SCRAPER ATTACHMENT FOR TRACTORS

Filed Feb. 29, 1932

Inventor
John A. de Nooy
by Orwig & Hague Atty's.

UNITED STATES PATENT OFFICE

JOHN A. DE NOOY, OF PELLA, IOWA

SCRAPER ATTACHMENT FOR TRACTORS

Application filed February 29, 1932. Serial No. 595,806.

The object of my invention is to provide a simple, durable and inexpensive scraper attachment for tractor wheels which may be easily and quickly attached to the tractor, and particularly adapted to be used in connection with that type of tractor wheels having two circumferential rows of lugs, said rows being spaced apart whereby the scraper may be operated between the rows of lugs for cleaning the periphery of the wheels and said lugs.

More specifically it is the object of my invention to provide an improved scraper attachment having a scraper blade formed of two members, one slidably mounted on the other with brakable means for supporting the blades in a normal working position in such manner that if the blade encounters frozen earth or other obstacles clinging to the wheel, the scraper blade may be moved longitudinally of its supporting member without injury to the blade, thereby allowing the blade to free itself of obstacles.

A further object is to provide in a scraper attachment for tractors employing a scraper blade improved means for detachably mounting the scraper blade to a suitable supporting member carried by the tractor.

My invention consists in the construction, arrangement and combination of the various parts of the device, whereby the objects contemplated are attained, as hereinafter more fully set forth, pointed out in my claims, and illustrated in the accompanying drawing, in which:

Figure 1 illustrates a segmental section of a tractor wheel and a portion of the mud guard carried thereby showing the manner in which my improved scraper blade is applied.

Figure 2 is a detail side elevation of the scraper blade, a portion of the blade being shown in section.

Figure 3 is a bottom view of Figure 2.

Figure 4 is a back view of the scraper supporting bracket.

Figure 5 is an enlarged detail sectional view taken on the line 5—5 of Figure 2.

Referring to the accompanying drawing, I have used the reference numeral 10 to indicate the rim of a traction wheel 11, and 12 indicates the lower end of the mud guard

carried by the tractor frame. Said guard includes a curved plate 13 having at its lower edge a reinforcing angle iron 14. One of the flanges of said angle iron extends forwardly toward the rim 10. The rim 10 is provided with two spaced circumferential rows of lugs 15 which are spaced apart in the usual manner.

My improved scraper comprises a bracket 16 formed of a pair of clamp members 17. Each of said clamps comprises a member 18 having a hook portion 19 at one end to engage the inwardly extending flange of the angle iron 14, and a coacting clamp member 20 having one end designed to engage the lower end of the member 13, the lower ends of the members 18 and 20 being curved to form recesses 21, said recesses being designed to carry a bolt or pivot 22.

A bolt 23 is provided for each of the clamps for clamping the members 18 and 20 to the angle iron 14 and to the lower end of the member 13, and for clamping the pivot member 22 in position in the manner clearly illustrated.

The members 17 are spaced apart a distance equal to the width of the scraper bar 24 which is pivotally mounted thereto at its upper end. The member 22 has a nut 25 for holding the bolt 22 in place, and at the same time provide means for drawing the members 17 snugly against the edges of the bar 24 to take up lost motion or wear. The bolts 23 may be loosened slightly to permit the member 17 to slide along the angle iron 14 to adjust the members 17 a proper distance apart, thereby providing means whereby the free end of the bar may swing freely about the bolt 22 as an axis, and at the same time have its free end held against lateral movement.

Slidably mounted on the free end of the bar 24 is a scraper blade 26 formed of a flat piece of metal having its outer end formed flat, while its inner end has its edges provided with rolled portions 27 in the manner illustrated in Figures 3 and 5 to form guides for receiving the bar 24.

Supported between the edges of the members 27 is a bridge member 28 welded in position. Openings 29 are drilled through the

bridge 28 and the front face of the member 26. An opening 30 is also drilled in the free end of the member 24 in alignment with the openings 29, said openings being designed to receive a brake pin 31 preferably formed of hard wood, in such manner that if excessive upward and outward longitudinal pressure is applied to the scraper blade 26, then the pin 31 will be sheared, permitting the member 26 to move longitudinally of the member 24, and thereby permitting the edge of the scraper to disengage the rim of the wheel 10.

The scraper blade 26 is supported in a downwardly and inwardly inclined position, as illustrated in Figure 1, with its free end engaging the rim 10 by means of a chain 32, one end of which is connected to the member 26 and its opposite end to the member 13 by means of a bolt 33.

Thus it will be seen that I have provided a scraper attachment for tractors which may be easily and quickly applied to the lower edge of the mud guard 13 by means of the clamps 17, the blade being supported in position by the chain 32. The blade 26 is designed to engage the rim 10 between the rows of lugs 15 in a tangent manner, so that as the rim 10 is rotated in a clockwise direction, as illustrated in Figure 1, any dirt clinging to the rim will be scraped therefrom, and at the same time clean the spaces between the adjacent lugs 15.

By forming the members 24 and 26 of sheet metal, it will be seen that said members may be built comparatively cheap and at the same time be very strong and light.

By providing the brake pin 31, means is provided whereby the scraper blade will be protected against injury in case it should engage chunks of earth frozen to the rim of the wheel, or rivet or bolt heads carried thereby.

By providing the chain 32 for supporting the free end of the scraper blade, means is provided for adjusting the distance that the free edge of the blade will operate from the rim 10. Under ordinary conditions, however, it is desirable to operate the scraper blade very close to the rim.

I claim as my invention:

1. A scraper attachment for tractor wheels, comprising a pair of clamp members, a scraper bar pivotally mounted between the clamp members, a scraper blade slidably mounted longitudinally of the scraper bar, a brake pin for securing the scraper blade at its operative position on said bar, and a chain for supporting said scraper blade in operative relation with the rim of a tractor wheel.

2. A scraper attachment for tractor wheels, comprising a pair of clamp members designed to clamp the lower edge of the mud guard of a tractor, means for adjustably clamping said members to said guard, a pivot member

carried by the free ends of said clamps, a scraper bar supported between said clamp members and to said pivot member, a scraper blade having its side edges rolled over the edges of said bar for slidably supporting said blade relative thereto, a bridge member connecting the free edges of said rolled portions, said bridge member, the blade and said bar being provided with openings for receiving a brake pin, a brake pin for said openings, and means for supporting the scraper blade tangentially to the rim of a tractor.

3. In a scraper attachment for tractors comprising a pair of clamp members, each of said clamps including a member having a hook portion at one end and its opposite end provided with a recess, a coacting clamp member having a recess in one end opposite the first recess, a pivot member carried by said recesses, a bolt for each of said clamps for clamping the clamp members to said pivot member and to the lower edge of a supporting member, a scraper bar supported between said clamps and pivotally mounted on said pivot member, a scraper blade slidably mounted on said bar, a brake pin for supporting said blade at its outer position of movement, and means for supporting said blade in contact with the rim of a tractor wheel.

4. A scraper attachment for tractors comprising a supporting bar, means for pivotally attaching one end of said bar to a tractor frame, a scraper blade having its side edges rolled over the corresponding side edges of said bar for slidably supporting said blade relative to said bar, a bridge member connecting the free edges of said rolled portions, said bridge member, said blade and said bar being provided with openings for receiving a brake pin, a brake pin in said openings, and means for supporting the scraper blade tangentially to the rim of a tractor wheel.
